(57) **CLAIM**

The ornamental design for a notched cylindrical fishing bobber, as substantially shown and described.

DESCRIPTION

FIG. 1 is a top perspective view of a notched cylindrical fishing bobber, showing the novel design, wherein the notched cylindrical fishing bobber resembles a shotgun shell; FIG. 2 is a bottom perspective view of the notched cylindrical fishing bobber shown in FIG. 1; FIG. 3 is a side elevational view of the notched cylindrical fishing bobber shown in FIG. 1; FIG. 4 is a side elevational view of the notched cylindrical fishing bobber shown in FIG. 1;

FIG. 5 is a side elevational view of the notched cylindrical fishing bobber shown in FIG. 1; FIG. 6 is a side elevational view of the notched cylindrical fishing bobber shown in FIG. 1; FIG. 7 is a close-up top view of the notched cylindrical fishing bobber shown in FIG. 1; FIG. 8 is a close-up bottom view of the notched cylindrical fishing bobber shown in FIG. 1; FIG. 9 is a top perspective view of the notched cylindrical fishing bobber shown in FIG. 1, wherein the spring is removed to clearly depict the "L"-shaped notch and wherein the notched cylindrical fishing bobber resembles a shotgun shell; FIG. 10 is a bottom perspective view of the notched cylindrical fishing bobber shown in FIG. 9; FIG. 11 is a side elevational view of the notched cylindrical fishing bobber shown in FIG. 9; FIG. 12 is a side elevational view of the notched cylindrical fishing bobber shown in FIG. 9; FIG. 13 is a side elevational view of the notched cylindrical fishing bobber shown in FIG. 9; FIG. 14 is a side elevational view of the notched cylindrical fishing bobber shown in FIG. 9; FIG. 15 is a close-up top view of the notched cylindrical fishing bobber shown in FIG. 9; FIG. 16 is a close-up bottom view of the notched cylindrical fishing bobber shown in FIG. 9; FIG. 17 is a top perspective view of an alternative embodiment of a notched cylindrical fishing bobber, wherein the notched cylindrical fishing bobber resembles a shotgun shell; FIG. 18 is a bottom perspective view of the notched cylindrical fishing bobber shown in FIG. 17; FIG. 19 is a side elevational view of the notched cylindrical fishing bobber shown in FIG. 17; FIG. 20 is a side elevational view of the notched cylindrical fishing bobber shown in FIG. 17; FIG. 21 is a side elevational view of the notched cylindrical fishing bobber shown in FIG. 17; FIG. 22 is a side elevational view of the notched cylindrical fishing bobber shown in FIG. 17; FIG. 23 is a close-up top view of the notched cylindrical fishing bobber shown in FIG. 17; and, FIG. 24 is a close-up bottom view of the notched cylindrical fishing bobber shown in FIG. 17.
The matter delineated in broken lines forms no part of the claimed ornamental design.
